UNITED STATES PATENT OFFICE.

FRANK C. WHEELER, OF MONTREAL, QUEBEC, CANADA.

LIFE-PRESERVER.

1,171,288.

Specification of Letters Patent.

Patented Feb. 8, 1916.

Application filed June 14, 1915. Serial No. 34,001.

To all whom it may concern:

Be it known that I, FRANK C. WHEELER, a citizen of the Dominion of Canada, and resident of the city of Montreal, in the Province of Quebec and Dominion of Canada, have invented certain new and useful Improvements in Life-Preservers, of which the following is a full, clear, and exact description.

This invention relates to improvements in life preservers, and the object of the invention is to provide a simple and inexpensive life preserver of the cork jacket type, which may be very easily applied, and in which the distribution of cork is such that proper flotation of the supported body is insured.

The ordinary cork jacket life preserver consists of a number of bars or slabs of cork, sewn up in canvas to form a wide belt with straight, parallel, upper and lower edges. Certain of the bars in some jackets do not extend fully to the upper edge, so that a recess is formed for the reception of the wearer's arms. These jackets, when properly worn, are supported by shoulder straps, which cross over and are tied around the body by a strap arranged adjacent the waist line. The shape and structure of these jackets is such that they form merely a broad belt, so that when a person wearing one is in the water, the support is so low that there is a very strong tendency to upset either forward or backward. When the jacket is put on in the hurry of emergency, the shoulder straps are more often than not uncrossed, allowing the jacket to slip even lower on the body, with the result that it is practically impossible for the wearer to remain upright in the water except by continuous effort, and in some cases, absolutely impossible. These facts have been demonstrated by recent marine disasters, and are here recited to accentuate the necessity and peculiar usefulness of the structural features of the present invention.

The life preserver according to this invention is in the form of a jacket, consisting of cork slabs sewn up in canvas, and having the lower edge sloping downwardly from the center to the ends, which meet at the front. The upper edge slopes downwardly from the center and from the ends, the lowest point being midway between the center and ends, so as to come under the wearer's arms. Straps are suitably posi-

tioned to adjustably secure the device to the body.

The particular shape of the jacket and the arrangement of straps, which do not require to be crossed but merely to be drawn tight around the neck and under the arms, provide for the location of the cork higher on the wearer's body than usual, and with the maximum amount of cork at the front, thus preventing a person falling face forward into the water and drowning.

In the drawings which illustrate the invention: Figure 1 is a plan view of the device extended flat. Fig. 2 is an end elevation of the device folded for storage. Fig. 3 is a side elevation of the device as worn.

Referring more particularly to the drawings, 11 designates a center or back slab of cork, 12 the side slabs, and 13 the front slabs. The side slabs 12 are of considerably less width than the back slab, and the front slabs together are of approximately the same width as the back slab, and are longer than the back slab, while the side slabs 12 are shortest of all. These slabs of cork or other suitable buoyant material are inclosed in canvas or similar fabric, which is so arranged that considerable webs 14 of the fabric extend between the cork slabs. The upper edge 15 of the device slopes downwardly from the center of the back slab, and the remote edges of the front slabs to approximately the center of the side slabs, while the lower edge 16 slopes downwardly from the center of the back slab to the remote edges of the front slabs, the inclination of the lines being such that the front slabs are longest, the back slab of intermediate length, and the side slabs shortest.

Ropes or straps 17 are attached at one end adjacent the center of the upper edge and extend toward the front of the device, where they pass through rings 18 secured in any suitable position on or adjacent the upper edge and adjacent the end edges. These ropes or straps may conveniently be knotted or otherwise enlarged, as shown at 19, to prevent disengagement thereof from the rings 18. Another rope or ropes 20 is attached at its approximate center to the center of the back slab a short distance above the lower edge, and extend toward the end edges, where it passes through rings 21 secured to the outer surface of the front slabs adjacent the end edges, and at some considerable distance from the bottom edge. The

ends of this rope are knotted or otherwise treated similarly to the ends of the rope 17, and for the same purpose.

When in storage, the side and front slabs 5 are superposed upon one another upon the back slab, as clearly shown in Fig. 2, and the whole tied by the rope 20, thus forming a compact, easily opened package.

When in use, the device is opened out to 10 substantially full length, and one arm slipped under each of the ropes 17, which it will be seen in Fig. 1 are in the form of loops, extending from front to back. The life preserver is then drawn on similarly to 15 a coat, and the ends of the rope 17 drawn as tightly as comfort will permit around the wearer's neck and tied. This drawing of the ropes has the effect of raising and holding the life preserver as high as possible on 20 the body. The lower rope 20 is similarly drawn tight and tied, thus securing the lower part of the device close against the body. The unfilled webs 14 of material between the cork slabs give the necessary flexibility to enable the device to be passed 25 around the body, and also provide for adjustment according to the size of the person wearing the device. For a child or slight person, these webs will be quite slack, and the edges of the cork slabs comparatively 30 close to one another, while for a very stout person the webs will be extended to full length. The total width of the cork slabs and of the webs 14 are therefore so proportioned 35 that the life preserver will fit equally well on persons of twenty-four to fifty-six chest measure. The long front slabs of cork increase the floating power in the front of the body to such an extent that it is impossible 40 for a person wearing the jacket to remain face forward in the water, and when applied in anything approaching the correct manner, the cork slabs project sufficiently upward to hold the forward fallen head of 45 an unconscious person out of the water. In fact, the large floating power in the front has the tendency of forcing the person backward in the water, thus keeping the mouth and nose as far as possible from waves and 50 spray. The drag of the ropes 17 in tighten-

ing draws all the cork slabs upwardly, but particularly the back slab, so that there is sufficient floating power disposed high up on the shoulders to absolutely prevent the wearer falling backward in the water, under 55 the influence of greater floating power at the front of the jacket.

Having thus described my invention, what I claim is:—

1. In a life preserver, a fabric jacket opening at the front having therein spaced slabs of cork, arranged at front, back and sides, the front slabs being longer than the back and the back slabs longer than the side slabs. 60

2. In a device of the character described, 65 a jacket comprising a fabric strip having the lower edge thereof sloping downwardly from the center toward the ends, and the upper edge thereof sloping downwardly from the center and ends to intermediate 70 points, whereby the ends of said strip are of greater depth than the center, and the center of greater depth than the points intermediate itself and the ends, and floats mounted in said fabric strip in spaced relation at the 75 center, ends and intermediate points.

3. In a life preserver, a fabric jacket, back, front and side floats secured therein, the front float being of greater depth than the back float and extending farther up and 80 down on the wearer than the back float, the back float being designed to lie against the back of the wearer's shoulders and upwardly to the base of the neck, and the side floats each smaller than the back float and 85 positioned against the sides of the wearer's body under the arms, ropes rigidly connected to the back float and passing over the wearer's shoulders and adjustable through the front floats, and a second rope connected 90 to the back float passing around the wearer's body under the arms and adjustable through the front floats.

In witness whereof, I have hereunto set my hand, in presence of two witnesses.

FRANK C. WHEELER.
